CLAIM

The ornamental design for headphones, as shown and described.

DESCRIPTION

FIG. 1 is a front perspective view of headphones showing my new design;

FIG. 2 is a front planar view of FIG. 1 thereof, showing section lines for other figures.

FIG. 3 is a back planar view of FIG. 1 thereof.

FIG. 4 is a left side fragmentary planar view of a portion of FIG. 1 thereof.

FIG. 5 is a right side fragmentary planar view of a portion of FIG. 1 thereof.

FIG. 6 is a top planar view of FIG. 1 thereof.

FIG. 7 is a bottom planar view of FIG. 1 thereof.

FIG. 8 is a fragmentary bottom planar view taken in the direction of line 8-8 of FIG. 2 to show the inside corner surface thereof; and,

FIG. 9 is a fragmentary perspective view taken in the direction of line 9-9 of FIG. 2 to show the inside corner surface thereof.

The features shown in broken lines depict environmental subject matter only and form no part of the claimed design.

1 Claim, 8 Drawing Sheets
